[57] ABSTRACT

This invention relates to the rapid processing of photographic material. The development takes place in a solution which contains a 3-pyrazolidone compound, a hydroquinone and a development anti-foggant.

7 Claims, No Drawings

PROCESS FOR THE PRODUCTION OF A PHOTOGRAPHIC PRINT

In the processing of most photographic print material of the silver halide emulsion type, the material after an imagewise exposure, is developed by immersion in a silver halide developing solution, fixed by immersion in a silver halide fixing solution, washed by exposure to a current of water and then dried. This invention relates to an improved photographic processing sequence of this type.

A substantial number of photographic prints are now made from photographic material which comprises a silver halide emulsion coated on a base which consists of a paper sheet laminated on both sides to a polyethylene layer. It is possible to process exposed photographic material of this type which is hereinafter referred to as polyethylene laminated photographic material relatively rapidly because processing solutions cannot be absorbed by the paper base since they never come into contact with it. Thus the washing stage in the normal processing sequence may be shortened very greatly since it is required to remove the excess processing chemicals and processing reaction products only from the emulsion and not from paper base as well. Interest, therefore, has arisen in trying to reduce the time required for the remainder of the processing sequence when processing polyethylene laminated photographic material.

The greatest period of time spent by an operator in the processing of polyethylene laminated photographic material is the time spent waiting to visually examine the exposed material after immersion in the developing solution. Photographic developing solutions have an appreciable induction period, that is to say 15 to 20 seconds elapse before any image appears on the print material after it has been immersed in the developing solution. As soon as the image starts to appear it develops very rapidly so that within 1 or 2 seconds after its first appearance the operator would be able to tell if the exposure time were correct and thus if the print is able to be used. This has the advantages of reducing the time wasted if the print is incorrectly exposed and of reducing the overall development time when correctly exposed.

It is the object of the present invention to provide a process for the production of a photographic print using polyethylene laminated photographic material wherein the induction period in the developer solution is considerably reduced.

Therefore according to the present invention in a process for the production of a photographic print using polyethylene laminated photographic material of the silver halide emulsion type which comprises the sequential steps of imagewise exposing the material, developing the latent silver image, fixing out the unexposed silver halide, washing the fixed material and drying the material there is provided the step of developing the exposed photographic material in a silver halide developer solution which comprises from 0.5 to 2 g per litre of a 3-pyrazolidone compound of the general formula,

wherein R₁ is a hydrogen atom or a methyl group and R₂ is a hydrogen atom or an alkyl or alkoxy group containing from one to four carbon atoms, together with hydroquinone or a substituted hydroquinone developing agent, the ratio by weight of the hydroquinone or substituted hydroquinone to the 3-pyrazolidinone compound being from 3 : 1 to 5 : 1 and there being present in the silver halide developing solution sufficient development anti-fogant to prevent a properly exposed print from being fogged, the pH of the developer being 10.0 to 11.5.

The preferred 3-pyrazolidone is 1-phenyl-3-pyrazolidone. Examples of suitable substituted hydroquinones are chloro-hydroquinone and methyl hydroquinone.

Any of the usual development anti-foggants may be used. However they must be present at an appreciably higher concentration in the developer solution than the concentration present in most normal developing solutions.

For example mercapto-tetrazole compounds which are well-known as development antifoggants may be used. Preferably the concentration of these compounds in the developer solution is within the range of 0.01 to 0.1 g/litre. The preferred mercapto-tetrazole for use in the invention is phenyl mercapto-tetrazole.

Other well-known development antifoggant compounds which may be used are nitrobenzimidazoles, for example 5-nitrobenzimidazole, nitroindazoles, for example 6-nitroindazole and 5-nitroindazole, benzotriazole and derivatives of benzotriazole for example 5-methylbenzotriazole. Preferably the concentration of these compounds in the developer solution is within the range of 0.05 to 0.5 g/litre.

15 The pH of the developer solution of use in the present invention is preferably 10.6, but can be within the range 10.0 to 11.5.

The developer solution of use in the present invention may contain in addition the normal constituents of developing solutions, e.g., sequestering agents, potassium bromide as a restrainer, antioxidants such as sodium sulphite. Water-miscible solvents e.g. ethylene glycol monomethyl ether, to help dissolve the 1-phenyl-3-pyrazolidone, may be present when the developer is compounded as liquid concentrate and is to be diluted 1 part plus 9 parts water for use. Concentrates for dilution in the range 5 fold to 20 fold may also be prepared.

3-Pyrazolidone compounds of the formula hereinbefore set forth and in particular 1-phenyl-3-pyrazolidone have found great use as photographic developing agents. However they are normally used in small amounts, e.g. from 0.05 to 0.2 grams per litre, together with relatively greater amounts of hydroquinone, e.g. from 5 to 15 g/litre to form a synergistic developing solution. When synergistic developing solutions of this type are used the induction period of print photographic material developed therein is about 20 seconds. However when polyethylene laminated photographic material is developed in the developing solution of the present invention the induction period is reduced virtually to nothing. This is both unexpected and very useful since it reduces very considerably the period required for the operator to have to wait in order to visually examine the photographic material in the developing solution while the image is developing. Further the process of the present invention enables the development time required in the processing of each polyethylene laminated photographic print to be reduced by between 20 seconds and 1 minute.

The following Example will serve to illustrate the invention.

EXAMPLE

The following developing solution was compounded:

Sodium sulphite, anhydr.	13	g.
Hydroquinone	3.1	g.
Potassium carbonate	15	g.
1-phenyl-3-pyrazolidone	0.8	g.
Sodium hydroxide	0.6	g.
Potassium bromide	0.5	g.
Phenyl mercapto tetrazole	0.025	g.
Ethylene diamine tetraacetic acid (disodium)	0.15	g.
Ethyleneglycol monomethyl ether	15	ml.
Water	to	litre
pH 10.60		

A sheet of polyethylene laminated photographic material bearing on one side a silver halide emulsion layer was imagewise exposed and then immersed in a tray containing the above developing solution. After less than one second a black image appeared. The print was allowed to remain in this developing solution for 60 seconds. Then it was removed and immersed for 30 seconds in a fixing solution having the following formulation. 25 20

Ammonium thiosulphate (60% w/w solution)	13.8	g.
Boric acid	7	g.
Sodium hydroxide	2.5	g.
Sodium metabisulphite	5	g.
Sodium sulphite, anhydrous	6	g.
Acetic acid, glacial	9	ml.
Water	to	litre

Then the material was washed for 1 minute in running cold water. Finally the print was dried for 30 seconds in a hot air cabinet. A fully developed dry print was obtained by this process after 3 minutes.

In another test using the same photographic material but wherein the formula of the developer used was:

Sodium sulphite, anhydrous	13	g.
Hydroquinone	3.1	g.
Potassium carbonate	10	g.
1-Phenyl-3-pyrazolidone	0.13	g.
Sodium hydroxide	0.55	g.
Potassium bromide	0.5	g.
Benzotriazole	0.06	g.
Water	to	1 litre.

The induction period of the material in the developer before any image appeared was 20 seconds and 120 seconds were required for full development. Thereafter the material was fixed, washed and dried as before. A fully developed dried print was obtained after 4½ minutes. Thus by the process of the present invention an overall saving of a little more than 1 minute in the processing of a print was obtained. However 20 seconds of this is time which would have been spent by the operator doing nothing but waiting to inspect the photographic material in the developer. The overall reduction in time is due to the greater activity of the devel-

oper. Nevertheless, the total time of the material in the developer is sufficiently long to enable the operator to obtain an acceptable print, e.g., removing it from the developer before the 1 minute, if it has been overexposed.

We claim:

1. In a process for the production of a photographic print using polyethylene laminated photographic material having coated thereon at least one silver halide emulsion layer which process comprises the sequential steps of imagewise exposing the material, developing the latent silver image, fixing out the unexposed silver halide, washing the fixed material and drying the material the improvement which comprises developing the exposed photographic material in a silver halide developer solution which comprises from 0.5 to 2 g per litre of a 3-pyrazolidone compound of the formula

- 30 wherein R_1 is a hydrogen atom or a methyl group and R_2 is a hydrogen atom or an alkyl or alkoxy group containing from one to four carbon atoms, together with a hydroquinone developing agent, the ratio by weight of the hydroquinone developing agent to the 3-pyrazolidinone compound being from 3 : 1 to 5 : 1 and there being present in the silver halide developing solution sufficient development antifoggant to prevent a properly exposed print from being fogged, the development anti-foggant being selected from the group consisting of a mercapto-tetrazole, a nitrobenzimidazole, a nitroindazole and a benzotriazole, the pH of the developer being 11.0 to 11.5.

- 45 2. A process according to claim 1 wherein the 3-pyrazolidinone is 1-phenyl - 3-pyrazolidinone.

3. A process according to claim 1 wherein the development anti-foggant compound is a mercaptotetrazole compound.

50 4. A process according to claim 3 wherein the mercaptotetrazole compound is phenyl mercaptotetrazole.

55 5. A process according to claim 3 wherein the concentration of the mercaptotetrazole compound in the developer is from 0.01 to 0.1 g/litre.

6. A process according to claim 1 wherein the development anti-foggant compound is a nitrobenzimidazole, a nitroindazole, a benzotriazole or a methylbenzotriazole.

60 7. A process according to claim 6 wherein the concentration of the development anti-foggant compound in the developer is from 0.05 to 0.5 g/litre.
